MASK

Howard R. Bierman and George E. Beckwith,
United States Navy

Application December 15, 1944, Serial No. 568,372

4 Claims. (Cl. 128—141)

(Granted under the act of March 3, 1883, as
amended April 30, 1928; 370 O. G. 757)

1

This invention relates to a mask or breathing apparatus of the type which includes a face piece that covers the face of the wearer and more particularly to means for retaining the mask in protective position over the face.

A further object of this invention is to provide a gas mask retaining means which is easily operable for quick manipulation in placing the mask in operative position as well as for quickly removing it from operative position.

A still further object of this invention is to provide a retaining means for gas mask that may be used independently of a helmet and irrespective of the presence or absence of a helmet, or may be used in conjunction with a helmet, and in either case have the same facility for quick emplacement or displacement of the mask.

A still further object of this invention is to provide an easily removable and replaceable mask particularly intended as an oxygen mask, but equally serviceable as a gas mask for protection against poison gases, which retaining means is adapted to hold the mask securely in place at all times.

Still another object of this invention is to provide a mask retaining means, particularly intended for an oxygen mask of the type which includes a microphone.

Still another object of this invention is to provide a gas or oxygen mask of the type which includes a microphone and wherein the air or oxygen tube enters from the side so as to be disposed over the wearer's shoulder rather than depend from the bottom, as customary, thus making this improved mask particularly useful for aviators by keeping the tube in a position where it will not be an interference.

With the foregoing and other objects in view, the invention consists in the construction, combination and arrangement of parts hereinafter set forth, claimed and illustrated in the drawing in which:

Fig. 1 is a perspective view of the mask retaining means in operative position, showing the right three-quarter profile of the wearer.

Fig. 2 is a perspective view showing the left three-quarter profile of the wearer.

Fig. 3 is a detailed enlarged view showing the mask gripping details.

Fig. 4 is a perspective view of the quick disconnect clamp in partially open condition, and

Fig. 5 is an enlarged fragmentary detail view of the clamp in closed position.

There is shown at 10 a gas or oxygen mask of the type having a microphone well 11 for sup-

2

porting a microphone, not shown, therewithin. Extending from one side of the mask 10 is an air or oxygen tube 12 having its entry port 13 substantially above the microphone well 11 and hence considerably above the lips of the wearer 14. Secured about the microphone well 11 is a wire ring 15 provided with four ears 16 and 17 and having its ends 18 secured by a wire clip 20. This wire ring 15 is sufficiently resilient that it 10 will clamp tightly about the well 11.

Secured to the helmet 21 as by means of snap fasteners 22 are four straps 23, each including an adjusting buckle 24, a hooked eye member 25 at the end thereof having a turned-back hook end 26. The hook ends 26 of the two straps 23 on the left side of the helmet 21 are intended to cooperate with the ring ears 16, the hook ends 26 of the other pair of strap members 23 on the right side of the wearer 14 are intended to cooperate with the turned-back ends 27 of a clip bar 28. This clip bar 28 forms part of a quick disconnecting mechanism 30, shown in Fig. 4, wherein a clip handle 31 is pivoted at 32 to a clip anchor 33 and the clip handle 31 beyond the 20 pivot points at 32 ends in hooks 34 adapted to secure about clip bar 28, as shown in Fig. 4. The clip anchor 33 extends between the ears 17, that portion of the wire ring 15 between ears 17 being crimped as at 35 as shown.

As thus described, the quick detaching mechanism 30 is intended for use by a right-handed individual so as to be easily accessible to his right hand, but if a left-handed individual is to wear it, it is only necessary to rotate the ring 180 degrees about the microphone well 11, including a similar rotation of the straps 23, or alternatively, the straps 23 may be left in position and the eye hooks 25 appropriately disconnected and reconnected. The helmet 21 may be omitted by merely lengthening straps 23 to extend and join behind the head.

In operation, the mask 10 is secured in position by snap fastening the straps 23 to the helmet 21, as at 22, before the helmet is placed on the head. 45 Then the clip handle 31 is passed under the clip bar 28 and rotated 180 degrees, securing the hooks 34 about the clip bar 28 and holding the mask in operative position, it being noted that the ends of the clip anchor 33 are turned back a bit to provide seats 36 in which clip bar 28 rests, as shown in Fig. 1. The use of goggles 37 is not interfered with by the presence of the mask 10 or mask securing straps 23. If the wearer wishes to remove the mask 10 quickly, he has but to lift the clip handle 31 from the position shown 50 55

in Fig. 1 or 3 through a 180 degree turn, which causes the handle hooks 34 to raise the clip bar 28 out of the seats 36 and separate therefrom, allowing the mask 16 to fall away from the face of the wearer, still being retained, however, by the straps 23 on the left side of the wearer.

Other modifications and changes in the number and arrangement of the parts may be made by those skilled in the art without departing from the nature of this invention within the scope of what is hereinafter claimed.

The invention herein described and claimed may be manufactured and used by or for the Government of the United States of America for governmental purposes without the payment of any royalties thereon or therefor.

What is claimed is:

1. A device for retaining a mask of the microphone well type on the face, said mask having an oxygen tube port above the well level, comprising

a ring resiliently secured on the mask microphone well, a plurality of ears extending from said ring, a plurality of adjustable straps having snap fastener means for securing to a helmet, an eye hook mounted on the end of each of said straps, a pair of said eye hooks cooperating with a pair of said ring ears, and a quick disconnecting mechanism mounted on the other pair of said eye hooks and the other pair of said ring ears.

2. A device for quick-detachably retaining a mask of the microphone well type on the face, comprising a ring resiliently secured on the mask microphone well, a plurality of ears extending from said ring, a plurality of adjustable straps having snap fastener means for securing to a helmet, an eye hook mounted on the end of each of said straps, a pair of said eye hooks cooperating with a pair of said ring ears, and a quick disconnecting mechanism mounted on the other pair of said eye hooks and the other pair of said ring ears.

3. A device for quick-detachably retaining a mask of the microphone well type on the face, comprising a ring resiliently secured on the mask microphone well, a plurality of ears extending

from said ring, a plurality of head-mounting straps having a hook mounted on the end of each of said straps, a pair of said eye hooks cooperating with a pair of said ring ears, and a quick disconnecting mechanism secured to the other pair of said hooks and the other pair of said ring ears, said quick disconnecting mechanism comprising a clip bar secured to said pair of hooks, an anchor bar mounted on said pair of ring ears, said anchor bar terminating in a pair of turned-back ends providing clip bar receiving seats and a handle clip having a pair of hooked ends and pivoted to the turned-back ends of said anchor bar whereby said clip handle may extend under said clip bar and be pivoted thereabout to place said clip bar in said anchor bar seats to hold the mask in position and may be rotated in an opposite direction to raise said clip bar out of said anchor bar seats for quick separation.

4. A device for quick-detachably retaining a mask of the microphone well type on the face, comprising a ring resiliently secured on the mask microphone well, a plurality of ears extending from said ring, a plurality of adjustable straps having snap fastener means for securing to a helmet, an eye hook mounted on the end of each of said straps, a pair of said eye hooks cooperating with a pair of said ring ears, and a quick disconnecting mechanism mounted on the other pair of said eye hooks and the other pair of said ring ears, said quick disconnecting mechanism comprising a clip bar secured to said pair of eye hooks, an anchor bar mounted on said pair of ring ears, said anchor bar terminating in a pair of turned-back ends providing clip bar receiving seats and a handle clip having a pair of hooked ends and pivoted to the turned-back ends of said anchor bar whereby said clip handle may extend under said clip bar and be pivoted thereabout to place said clip bar in said anchor bar seats to hold the mask in position and may be rotated in an opposite direction to raise clip bar out of said anchor bar seats for quick separation.
